UNITED STATES PATENT OFFICE.

WILLIAM H. CARTER, OF NEEDHAM HEIGHTS, MASSACHUSETTS.

DESIGN FOR A BORDER FOR KNITTED AND OTHER FABRICS.

43,336.

Specification for Design.

Patented Dec. 10, 1912.

Application filed September 12, 1912. Serial No. 720,102. Term of patent 14 years.

To all whom it may concern:

Be it known that I, WILLIAM H. CARTER, a citizen of the United States, residing at Needham Heights, in the county of Norfolk and State of Massachusetts, have invented a new, original, and ornamental Design for Borders for Knitted and other Fabrics, of which the following is a specification, reference being had to the accompanying drawing, forming part thereof.

The figure is a plan view of a portion of the border showing my design.

I claim:

The ornamental design for a border for knitted and other fabrics, as shown.

In testimony whereof, I have signed my name to this specification in the presence of two subscribing witnesses.

WILLIAM H. CARTER.

Witnesses:

SAMUEL CUNNINGHAM,
PRESTON MITCHELL.
